UNITED STATES PATENT OFFICE.

HINES A. POWERS, OF FARRY, OKLAHOMA.

ROAD-SCRAPING MACHINE.

1,319,615.

Specification of Letters Patent.

Patented Oct. 21, 1919.

Application filed August 12, 1918. Serial No. 249,494.

To all whom it may concern:

Be it known that I, HINES A. POWERS, a citizen of the United States, residing at Farry, in the county of Woods and State of Oklahoma, have invented certain new and useful Improvements in Road-Scraping Machines, of which the following is a specification.

My invention relates to improvements in road scraping machines, and particularly to that type of road scraping machine adapted to being propelled in front of suitable traction means, having its working mechanism controlled from the operator's seat on the traction means, and it is the principal object of the invention to provide a road scraping machine capable of excavating through hills, likewise, filling grades between hills and approaches to bridges, or similar work of grade or mound building; such operations being accomplished, at all times, from a position upon the completed surface of the roadway, as in opposition to all contemporary machinery wherewith is presupposed a passage way for the traction power.

It is also an object of the invention to provide manual means for moving the shovel to dumping or raised position, irrespective of the means for automatically raising the same after it has been filled with earth or other matter.

The invention also aims to provide novel guide ways or tracks for retaining the shovel in proper position and for expedient means for insuring the scraping, loading and unloading operations of the shovel.

The invention consists, furthermore, in the novel arrangement and combinations of parts of the machine as well as in the details of construction of the same, all of which will be more fully described in the following specifications, and then finally embodied in the clauses of the claim, which are appended to this specification and which form an essential part of the same.

The invention is clearly illustrated in the accompanying drawings, in which:

Figure 1 is vertical longitudinal section through the improved machine.

Fig. 2 is a top plan thereof.

Fig. 3 is a side elevation of the same.

Fig. 4 is a vertical transverse section.

Fig. 5 is a fragmentary detail in section showing the locking means for the excavating shovel whereby the same is maintained against sliding movement.

Fig. 6 is a detail partly in section showing the shovel locking means in elevation.

Fig. 7 is a fragmentary detail partly in section of the means for manually receiving the shovel.

Fig. 8 is a disassembled detail in perspective of the shovel locking means, and

Fig. 9 is a similar view of the switch means used in connection with the forward or front guide ways or tracks.

Similar characters of reference refer to similar parts throughout the several views of the drawings.

Having more particular reference to the drawings, 1 represents the substantially rectangular shaped frame of the machine, the forward end of which is provided with spaced bearing collars 2 for receiving spindles 3 carried upon the upper ends of forked bearing brackets 4, which bearing brackets as will be noted, support wheels 5 therein.

Rigidly supported on the opposite sides of the frame 1 is an inclined supporting element designated by the numeral 6, it being noted in this connection, that the said element comprises a pair of inverted V-shaped structures, certain of the sides of which are slotted as at 7 and have their lower portions bent laterally or horizontally rearwardly as 85 indicated by the numeral 8 and then obliquely downwardly and forwardly as at 9, whereupon the same are secured to the adjacent portions of said sides by rivets or similar fastening device as at 10. Supported in bearings arranged in the top of the element 6 is a drum 11, one end of which is provided with a spiral gear 12 engaged by a worm gear 13 carried upon the upper end of an obliquely disposed shaft 14, the lower end of the shaft having a bevel gear 15 mounted thereon and meshing with suitable drive means, hereinafter more fully described. It is to be noted, that the gear 15 is loosely mounted on the lower end of the shaft 14 and is connected thereto through the medium of a slid able clutch element 16 with which an operating lever 17 is engaged and pivotally mounted on an adjacent portion of the frame 1.

Suitably secured at the forward end of the frame on opposite side thereof is a pair of brackets 18, preferably of the shape shown in Fig. 3 of the drawings, each having ways 19 and 20, respectively, the way 20 being in communication with the way 19 at a point adjacent to its rear end, and at this intersection of the ways is located

a switch frog or element 21, which normally closes communication between said ways, the frog or element 21 being suitably pivoted for swinging movement and is adapted 5 to be moved to different positions to cause the switching of the shovel supporting rollers 28 for their movement in proper directions in said ways, as hereinafter fully described.

10 Carried upon the pivot supporting the switch frog or element 21 is a bell crank trip lever 22 which moves independently of said frog or element and when the latter is in normally closed position one of the limbs 15 or arms of said lever 22 extends vertically across the path of the way 19 for action by the shovel supporting rollers 28 after passage into said way to control the working of the switch frog or element. The lever 22 has formed thereon near the ends of its limbs or arms bosses 24 which are adapted to be alternately engaged in a pocket or recess 25 in the bracket 18 to hold the lever 22 in its several shifted positions for the automatic action of the switch frog or element 21 at predetermined intervals.

Connected to the switch frog or element 21 and the lever 22 is a spring 23 as shown 30 in Fig. 9 of the drawings, which spring causes the raising of said frog or element 21 when the lever 22 is shifted to one position, and this frog or element 21 is also lowered by said spring 23 when the lever 35 is shifted to the other position.

It will thus be understood that the frog or element 21 will be opened and closed with relation to the ways 19 and 20 to control communication between the same for permitting the proper travel of the shovel supporting rollers 28 in the dumping operation of the machine.

An excavating shovel 26 is provided and has bracket arms 27 secured to the forward 45 portion thereof which bracket arms support a cross rod 27', having rollers 28 mounted on its opposite end receivable in the ways 19 and 20 of the brackets 18, while the rear portion of said shovel has a similar rod 29' arranged thereon and on which rollers 29 are mounted, these rollers in turn being received in the slot or track 7 formed in each of the adjacent sides of the element 6. In the operation of the shovel, when 50 raised, the rollers 28 travel upwardly in the ways 20 and in their movement will act upon the switch frogs or elements 21 which are normally closed so as to open the same to allow the passage of said rollers into 55 the ways 19, whereupon the switch frog or element closes by gravity, thus closing the ways 20 to the rollers 28 after their passage therefrom, and at this time the levers 22 are in a position so that certain limbs or 60 arms thereof will intersect the path of the 65

ways 19 to be engaged and operated upon by said rollers 28 when moved forwardly therein beyond the frogs or elements, thereby raising the latter. Now on the dumping of the shovel the retrograde movement of 70 the rollers 28 in the ways 19, that is to say, upwardly and rearwardly therein, the switch frogs or elements 21 will be closed on movement of the rollers thereover and immediately after the rollers pass over said frogs or elements the same will automatically rise again to open position to permit the rollers 28 to move downwardly into the ways 20, and in such travel thereof, the levers at this time being in shifted position 75 to have certain of the limbs or arms thereof depend in the path of the said ways 20 will be acted upon by the rollers for the shifting of the levers to move the same to their first position thereby causing the positive 80 closing of the switch frog or element 21 and thus shutting off communication between the ways.

These operations are repeated by each 85 dumping action of the machine.

90 Bell crank levers 30 are secured to the axles of the several rollers 29. The axles being fitted on their outer ends with clutch elements 31. These, as will be noted, have recesses 31' formed in their outer faces 95 adapted to be engaged by projections 32 formed upon the inner faces of hinged clutch elements 33 carried upon slides 34 slidably mounted in any suitable manner in the element 6 as shown at 34. The leaf springs 100 35 are secured to the clutch elements 33 just below where the hinge element 33 is hinged, as shown at 36, and have bearing upon the clutch elements 33, thus, normally forcing the latter inwardly to positions whereat they 105 will engage with the recesses 31' formed in the elements 31 whereby the scraper can be adjusted and held in any adjusted position 110 in the sides of the portions 9 of the supporting element. Otherwise, there would positively be no adjustment to the scraper and it would be compelled to return to the lower depth or position of adjustment, regardless of the depth of the plowing or any 115 other condition that might make a shorter depth essential. It, of course, will be understood that when the clutch elements 33 are engaged with the clutch elements 31, movement of the shovel 26 will be positively 120 prevented, thus allowing the cutting edge of the same to be effectually engaged with the surface or a roadway or the like being excavated. However, when the clutch elements 31 are rotated to cause disengagement 125 of the projections 32 in the face of 33, the rollers will be then permitted to slide upwardly in the obliquely disposed portions 9, due to the resistance offered by the engagement of the cutting portion of said shovel 130 with the dirt or like matter arranged on

the roadway. The clutch element can be swung outwardly against the resistance of the spring to disconnect said clutch element from the clutch element 31 as will be clearly apparent. Screw threaded boxings 37 are carried by the movable clutch element 33 and receive therethrough screw threaded rods 38, the lower ends of which are journaled in suitable bearings 38' formed on the lower ends of the portions 9 while the upper ends of the same are journaled in bearings 39 and carry bevel gears 40 thereon meshing with gears 41 and 42 loosely mounted on a transversely disposed shaft 43, the opposite ends of which are journaled in bearings 44 arranged on the opposite sides of the frame 1. Clutch elements 45 are splined to the shaft 43 and are adapted to be engaged with corresponding clutch elements 46 and 47 carried by the gears 41 and 42. Arranged adjacent the gear 42 is another bevel gear 48, which as will be noted, is adapted to mesh with the gear 15 mounted on the lower end of the shaft 14. As means for engaging the clutch elements 45 with their respective elements 46 and 47, there is mounted adjacent the shaft 43 a bell crank lever 49, one end of which is loosely engaged with the adjacent clutch element 45 while another of the ends of the same is pivotally engaged with a connecting rod 50 having the outer end thereof connected to a yoke 51 having engagement with the collar of the remaining clutch element 45. An operating lever 52 is pivotally connected to the bell crank lever 49 and as will be understood, extends rearwardly to the tractor seat whereat the same may be conveniently engaged by an operator. Obviously, by shifting the rod 52, the clutch elements 45 may be engaged with their respective clutch elements 46 and 47 and as a consequence, rotary motion will be imparted to the screw threaded shafts 38. By this means, the shovel 26 will be caused to move upwardly or downwardly along the inclined portions 9, whereupon the shovel will be raised to dumping position by means of a cable 53 having certain ends engaged with the windlass 11 while the remaining ends are engaged with the bell crank levers 30, which as will be noted, are normally maintained in operative positions by means of contractile coiled springs 54 or the same can be moved downwardly and be held in proper position for loading, the latter being determined by the depth of the plowing and the position of the gage wheels relative to the furrows.

As means for imparting rotary motion to the shaft 43, beveled gears 55 and 56 are loosely mounted thereon and are adapted to alternately mesh with a drive bevel gear 57 mounted on the adjacent end of a drive shaft 58, which shaft, as will be understood, extends into engagement with a suitable

source of power arranged on the tractor to which the frame of the machine is attached, not shown; such engagement of the gears being effected by a clutch splined to the shaft 43 and mounted between the gears 55 and 56 which are provided with clutch elements capable of being engaged optionally by said clutch, which is operated by a lever arranged convenient to the operator's seat on the tractor. Obviously, by engaging the gear 55 with the drive gear 57, a forward rotary motion will be transmitted to the shaft 43 and by disengaging the gear 55 therefrom and engaging the gear 56 there-with a reverse motion will be transmitted to the shaft 43.

The rear extremities of the frame 1 are provided with suitable hinge or pivotal connections, not shown, adapted to be engaged with the frame of a tractor or like means, also not shown. In this way, it will be understood that the scraping machine will be pushed over the road or highway to be graded and as a consequence, permit it to properly function; further that relative movement between the machine and tractor will be permitted.

Connected to the sides of the element 6, opposite the sides having the track ways 7 formed therein, by means of contractile coiled springs 59 is a hanger 60, the lower end of which is hooked as at 61 and arranged to engage the axles supporting the rollers 28 carrying the forward portion of the excavating shovel 26 and movable through the track ways 19 and 20 formed in the brackets 18. By so engaging the hanger 60 with the axle 27, which is effected manually, it will be understood that the shovel will be immediately returned to its upper position with respect to the brackets 18 after the load of dirt or other matter has been dumped or discharged therefrom, hence, rendering the return to this point automatic.

The operation of the improved grading machine may be reviewed as follows:

The excavating shovel is arranged in its lowermost position with relation to the portions 9 and brackets 18, the rollers 28 being received at the lower ends of the track ways 20 formed in said brackets 18. At this time, the clutch elements 31 and 33 will be engaged and as a consequence, sliding movement of the excavating shovel with relation to the machine frame will be positively prevented. That is, the excavating shovel may be held in any adjusted position along the oblique or inclined tracks, the clutch element 33 engaging the clutch element 31 and thus holding the wheels 29 in an adjusted position whenever the operator desires. Therefore, when the forward end of the shovel is engaged with the dirt or other matter arranged on the roadway, it will act to effectually remove the same and load it

thereinto. When the shovel has been fully loaded, it is then necessary to raise the same to a point on the frame 1 out of engagement with the roadway in order that the earth 5 may be conveyed to a point or dumped. To accomplish this the clutch element 16 is engaged with the element carried on the bevel gear 15, whereupon the shaft 14 is caused to rotate, thus removing the slack 10 from the cables 53 and causing the same to rock their respective bell crank levers 30, which in turn, will cause disengagement of the clutch elements 31 and 33. The clutch 15 16 is now disengaged from its respective clutch element on the gear 15 and upon the continued advance of the machine, the resistance offered to the shovel by reason of its engagement with the surface of the roadway will cause the same to be forced rearwardly and consequently upwardly on the 20 brackets 18 and the inclined portions 9 of the track ways 7. When at this point, the clutch 16 is reengaged with the clutch element carried on the gears 15, again rotating the shaft 14 and winding the cable 53 upon the windlass 11, thus raising the rear end of 25 the excavating shovel 26 to dumping position and causing its contents to be discharged therefrom. During such raising of the rear end of the excavating shovel, the forward end of the same will be caused to move downwardly over the track ways 19 formed in the brackets 18, thereby insuring the full discharge or dumping of the load. 30 When the load has been dumped from the shovel, the spring 59 will then act to immediately return the same to a position on the brackets 18 adjacent the junction of the track ways 19 and 20. During the return of the forward end of the shovel, the frog 21 35 will be actuated through the medium of the trip lever 22 to again establish communication, that is, open the track ways 20, whereupon the rollers 28 will enter the same and return to their normal positions. Should it be desired to operate the shovel 26, that is 40 raise the same, irrespective of the automatic means, the screw threaded shafts 38 are rotated due to their connection with the reverse shaft 43, thus throwing the shovel upwardly by reason of the connection between the screw threaded boxing 37 carried thereby and said screw threaded rods 38. The shovel may be returned to its lowermost 45 position by reversing rotation of the screw threaded shafts 38 through the medium of the gear 56; the same being brought into engagement with the drive gear 57, while the gear 55 is disengaged therefrom. 50 From the foregoing it will be appreciated by workers skilled in the art that I have provided an exceedingly simple and efficient form of road scraping or grade building machine. By reason of the novel mounting 55 of the excavating shovel, it will be under-

stood that the pitting of the surface of the roadway, either in grading or filling operations, will be positively prevented; primarily because of the manner in which said shovel is locked in adjusted positions with 70 relation to such surface. It also follows that since the traction will operate at all times upon the completed surface of a roadway that draft is reduced to a minimum, and as a consequence a material saving in time 75 and labor, as well as operating cost is effected upon part of a user. By reason of the manner in which the excavating shovel is arranged to move into operative and dumping positions, I am further enabled 80 to eliminate considerable waste of time which might otherwise be incurred with the usual form of excavating shovel for scraping machines, in that the scraper is pushed instead of being pulled, and, therefore, 85 makes its own road instead of requiring that the road be first prepared.

Manifestly, the construction shown is capable of considerable modification, and such modification as is within the scope of 90 my claims, I consider within the spirit of my invention.

I claim:

1. In a road scraping machine, a frame, inclined supporting means arranged on said frame, a shovel having the rear end of the same slidably engaged with the inclined supporting means, other supporting means arranged adjacent the forward end of the frame and slidably engaged by the forward 100 end of said shovel, means arranged on the inclined supporting means engageable with the shovel for locking the same against sliding movement, at times, and other means for raising the shovel to dumping position. 105

2. In a road scraping machine, a frame, inclined supporting means arranged in proximity to the rear end of said frame, other inclined supporting means arranged in proximity to the forward portion of the frame 110 having a plurality of track ways formed therein, a shovel having its opposite end slidably engaged with the inclined supporting means and the track means of the forward supporting means, means arranged on 115 the inclined supporting means engageable with a portion of the shovel for preventing sliding movement of the same, at times, and other means for raising the rear end of the shovel to dumping position. 120

3. In a road scraping machine, a frame, a shovel slidably mounted on said frame, screw threaded shafts mounted adjacent the rear portion of the frame and connected to the adjacent portion of said shovel for 125 raising the same, and means for imparting rotary motion to said shafts.

4. In a road scraping machine, a frame, inclined supporting means arranged on the frame adjacent the rear end of the same, 130

- other supporting means arranged on the frame adjacent the forward end thereof having a plurality of inclined track ways formed therein, a shovel slidably engaged 5 with the supporting means arranged adjacent the rear and forward ends of the frame, means arranged on one end of the supporting means engageable with portions of the shovel for preventing sliding movement of 10 the same, at times, and means for raising the rear end of the shovel to dumping position, a plurality of obliquely disposed screw threaded shafts mounted in bearings adjacent the rear end of the frame having connection 15 with the adjacent end of the shovel, and means for imparting rotary motion to said shafts.
5. A road scraping machine adapted to be pushed and comprising a frame horizontally positioned, supporting means at the forward end of the frame, the rear end of the frame being designed to be supported upon a tractor, a shovel mounted in the frame for angular sliding movement to receiving and dumping positions, and means for causing the elevation of the rear portion of the shovel by advancement of the frame, and means for automatically returning the shovel to a horizontal scraping position. 20
20. A road scraping machine adapted to be pushed and comprising a frame horizontally positioned, supporting means at the forward end of the frame, the rear end of the frame being designed to be supported upon a tractor, a shovel mounted in the frame for angular sliding movement to receiving and dumping positions, and means for causing the elevation of the rear portion of the shovel by advancement of the frame. 25
6. A road scraping machine adapted to

be pushed and comprising a frame horizontally positioned, supporting means at the forward end of the frame, the rear end of the frame being designed to be supported upon a tractor, a shovel mounted in the frame for angular sliding movement to receiving and dumping positions, means for causing the elevation of the rear portion of the shovel by advancement of the frame, and means for automatically returning the shovel to a horizontal scraping position. 30

7. The combination with a tractor, of a road scraping machine adapted to be disposed in front of the tractor, said machine comprising a frame supported at its rear end upon the tractor, caster wheels at the forward portion of the frame, a shovel spanned by the frame and on each side of which said wheels are located, guiding tracks at the front and rear ends of the frame adjacent each side thereof for guiding the shovel in the raised and lowered positions, means for elevating the shovel in said tracks, and means for returning said shovel to lowered position. 35

In testimony whereof, I affix my signature hereto. 40

HINES A. POWERS.
